UNITED STATES PATENT OFFICE.

LEE S. CHADWICK, OF SHAKER HEIGHTS, OHIO, ASSIGNOR TO THE CLEVELAND METAL PRODUCTS COMPANY, OF CLEVELAND, OHIO, A CORPORATION OF OHIO.

WICK STOP MECHANISM FOR OIL BURNERS.

Application filed January 12, 1922, Serial No. 528,814. Renewed June 6, 1923.

To all whom it may concern:

Be it known that I, LEE S. CHADWICK, a citizen of the United States, residing at Shaker Heights, in the county of Cuyahoga and State of Ohio, have invented a certain new and useful Improvement in Wick Stop Mechanism for Oil Burners, of which the following is a full, clear, and exact description, reference being had to the accompanying drawings.

This invention relates to automatic wick stop mechanism for liquid fuel burners and is of the same general character as the inventions which constitute the subject matter of my former applications Serial Nos. 448,108, 448,109 and 449,842, the two first mentioned cases having been filed February 26, 1921 and the latter March 5, of the same year. A further development of the same subject matter is exhibited in an application entitled "Automatic wick stop" and filed by me concurrently herewith.

The primary object of my present invention, like that of my other inventions above referred to, is to provide stop mechanism for limiting the upward movement of the wick and which controls the wick raising means and is, itself, under the direct control of the wick, having a part which engages the burned portion of the wick and which is actuated thereby for throwing the mechanism into cooperation with the wick raising means, said part withdrawing from the burned portion of the wick after it has served the aforesaid purpose. A further object is to utilize, for such part or actuator, the flame spreader that constitutes a part of burners of the character to which my invention relates, the spreader after serving its purpose as an actuator of the aforesaid mechanism, withdrawing to a position wherein it functions purely as a flame spreader.

A further and more specific object and one which distinguishes my present invention from the others referred to, is the provision of means for temporarily throwing out of commission the wick raising mechanism so that a dwell of the wick is effected during which the flame spreader may be elevated to its high position, the wick raising mechanism thereafter resuming its operative condition to elevate the wick further until its operation is arrested by the stop mechanism.

Further objects, relating more to structural improvements, will appear as this description proceeds.

The several objects of the invention are obtained in the embodiments of the invention illustrated in the drawings accompanying and forming part hereof and wherein Fig. 1 is a sectional side elevation of a burner incorporating one form of my invention; Fig. 2 is a detail of a rack and gear arrangement used in connection with my invention; Fig. 3 is a view similar to Fig. 1 showing the spreader and the parts movable therewith partially elevated and showing the wick raising means thrown out of commission, the position of the parts when the spreader is in high position being suggested by the dotted lines; Fig. 4 shows the parts of Fig. 2 in what may be termed "intermediate" position; Fig. 5 shows the same parts as Fig. 4 in what may be termed "high" position; and Figs. 6 and 7 are views similar to Figs. 1 and 2 of a modified form of the invention.

The burner proper, in both forms of the invention, is shown as comprising inner and outer wick tubes 1 and 2, respectively, which are joined at their lower ends by an annular wall 3 so as to enclose a space 5 within which a tubular wick 6 is contained, the same being equipped with a carrier 7.

In the first form of the invention, that illustrated in Figs. 1 to 5, a rod 10 depends from one side of the carrier 7 through a suitable stuffing gland 11 that is applied to the lower ends of the wick tubes, and a suitable distance below the gland the rod is provided with teeth 12 constituting thereof a rack that meshes with a pinion 13 that is loosely mounted upon the wick raising spindle 14. The pinion 13 is shown as provided with a clutch member 15 which cooperates with a clutch member 16 that is slidable on the spindle 14, the pinion 13, with the clutch member 15, being confined against longitudinal movement by collars 18 disposed on opposite sides thereof. The clutch member 16 connects through a neck 19 with a disk 20 between which and a collar 21 on the spindle there is compressed a spring 22 which tends to force the clutch member 16 into engagement with the member 15.

The spindle 14 is journaled within brackets 24 and 25 that depend from the burn-

er, and it is held against endwise movement therein by the engagement of one of the collars 18 with the adjacent bracket and by the engagement of a similar collar 26 with the other bracket.

A spanner 30 is movably supported within the inner wick tube 1 a suitable distance below its upper end, and a flame spreader 31 is adapted to be detachably connected thereto as by means of hooks 32. A flange 33 of the flame spreader projects over the wick space in a position to be engaged by the wick when the latter is elevated. A bar 35 is secured to and depends from the spanner 30 and at its lower end terminates in a loop 37 which surrounds a gear 38 that is secured to the spindle 14. This loop has, on its inner side, a single tooth 39, which, when the parts are in normal or low position is downward beyond the reach of the teeth of the gear 38. A segment 40 is pivoted, at 41, to a lateral extension 42 of the loop 37 and is limited in movement relative to the loop by stops 43 and 44 that are carried by the latter. The segment is normally held downward against stop 43 by a spring 45 which has one of its ends connected to the end of the segment 40 remote from its toothed end, while the opposite end of the spring is anchored at 46 to the loop. A suitable distance above the loop 37, the bar 35 carries a roller 48 that is adapted, when the bar is elevated, to override a roller 50 mounted at the outer end of the horizontal branch 35 of an angle lever 51 that is pivoted at 52 to an extension of the bracket 25. The lower end of the other branch of this lever is disposed between the clutch member 16 and the disk 20 and is adapted to engage said disk and retract the clutch member 16 from engagement with the clutch member 15 against the action of spring 22 when it is swung through the cooperation of the roller 48 with the roller 50. The clutch member 16 is held against rotation with respect to the shaft as by means of a pin 53 which extends through a slot 54 in the neck 19.

From the foregoing description it is evident that when the spindle 14 is turned by means of a hand wheel 55 that is secured to its outer end it will move the rack 12 through the intervention of the pinion 13 and clutch members 15 and 16. Assuming that the spindle is turned in a direction to elevate the wick, this action will continue until the upper end of the wick engages the flange 33 of the flame spreader 31 and elevates the spreader which will result in a lifting of the spanner 30 and an elevation of the bar 35 connected thereto. Just as soon as the bar 35 has been raised sufficiently to engage the tooth 39 of the loop 37 with the teeth of the gear 38, this gear, which, as will be observed from the drawings, is shown as of greater diameter than

the pinion 13, will elevate the bar 35 at a considerably faster rate of speed than that at which the wick is travelling and consequently will immediately lift the spreader from the wick. This action is desirable, though not essential. As the bar rises, its roller 48 engages the roller 50 and swings the lever 51 in a direction to disengage the clutch member 16 from the clutch member 15, thus freeing the pinion 13 from the spindle, allowing these parts, with the rack 12 and consequently the wick 6, to remain at rest until such time as the roller 48 passes beyond the roller 50, releasing the lever 51 and permitting the spring 22 to re-engage the member 16 with the member 15 and thus lock the pinion 13 again to the spindle 14. By this time, the tooth 39 of the loop 37 has passed above the gear 38, as shown in Fig. 5, the teeth of the segment 40 having in the meantime been brought into mesh with the gear. (This maximum elevation of the loop 37, with the bar 35, marks the "high" position of the flame spreader.) The gear, therefore, and the spindle 14 as well, may continue to rotate in a direction to elevate the wick until the segment 40 engages the stop 44. This constitutes the stop which limits the upward movement of the wick. To return the parts to their former positions requires only the reversal of the foregoing operation. When it is desired to clean or remove the wick, the spreader may be disengaged from the spanner 30 by turning it sufficiently and in the proper direction to disengage its hooks 32 from the parts of the spanner wherewith said hooks cooperate.

In the form of the invention illustrated in Figs. 6 and 7, the construction of the burner is altered somewhat from that previously described and resembles to a certain degree the form of burner shown and described in detail in my copending application Serial No. 448,108 above referred to. Vertical walls 60, spaced a suitable distance apart, extend diametrically across the inner wick tube 1 and the space between them is closed at its lower end by a wall 61, said space opening through slots in the inner wick tube into the wick space 5. A cross member 62 has its opposite ends connected to the wick carrier 7 and at its center is secured to a rod 64 which rises a suitable distance above the top 65 that closes the upper end of the space between the walls 60. A rack carrying member 66 is attached to the upper end of the rod 64 and extends laterally and then downwardly therefrom. A rack 68 is fastened to and depends from the lower end of the rack carrying member 66 in a position to cooperate with a wide faced pinion 69 that is secured to the wick raising spindle 70 which is equipped, at its outer end, with the usual hand wheel 71. The spindle is journaled in a bracket 72 that

depends from the adjacent side of the burner. The rack member 66 is capable of yielding in a direction longitudinally of the spindle 70 a distance sufficient to withdraw 5 its teeth from those of the pinion and into register with a smooth portion 73 thereof. A spring 75, shown as carried by the inner wick tube 1, bears against the rack carrying member 66 and tends to move it in a 10 direction to engage the rack 68 with the teeth of the pinion 69.

A spanner 76 is slidable within the upper end of the inner wick tube and pivotally connected to it at 77 is a bar 78 which terminates at its lower end in a loop 79 that surrounds the pinion 69. This loop is similar to the one described in connection with the former embodiment of the invention and has one tooth 80 for cooperation with the 20 teeth of the pinion, and pivoted to the loop, as by means of the pin 81, is a segment 82 which is normally held against a stop 83 by a spring 84 so that the teeth of the segment form, in effect, a part of a rack of 25 which tooth 80 is a member. A stop 85 limits the upward movement of the segment 82. The bar 70 carries a roller 88 which is adapted to override a roller 89 that is supported through a bracket 90 from the adjacent wall 60. The rack carrying member 66 has a roller 91 which bears upon the near side of the bar 78. A flame spreader 93 is adapted to be locked to the spanner 76 as by means of its hooks 94.

35 In this form of the invention, when the spindle 70 is turned in a direction to elevate the wick by reason of its operative connections therewith through the rack 68, member 66, rod 64, and cross member 62, it 40 will cause the wick to engage the spreader and through it lift the spanner 76. This will result in the roller 88 riding over the roller 89, causing the bar 78 to be swung in a direction to displace the rack carrying member 66 laterally against the tension of 45 spring 75 sufficiently to remove the rack 68 from the toothed portion of the pinion 69, at which time all movement of the wick will cease until the roller 88 passes beyond the roller 89 after which the rack may 50 resume its cooperation with the toothed portion of the pinion. The operation thus far results in the tooth 80 of the loop 79 passing beyond the pinion 69 so that further 55 elevation of the spreader is prevented; and thereafter the spindle 70 may be turned to elevate the wick until the segment 82, with the teeth whereof the pinion 69 is now in mesh, is moved against the stop 85, when 60 the pinion will be locked against further rotation in a direction to raise the wick.

Having thus described my invention, what I claim is:

1. In a burner of the character set forth, 65 the combination of wick raising means, a

member arranged to be engaged and moved by the wick, and operative connections between said member and the wick raising means whereby the latter is temporarily thrown out of operation through the movement of said member by the wick. 70

2. In a burner of the character set forth, the combination of wick raising means, a member arranged to be engaged and moved by the wick, and operative connections between said member and the wick raising means whereby the latter is momentarily thrown out of operation through the initial movement of said member by the wick, and said member is moved out of contact with 80 the wick by the wick raising means. 75

3. In a burner of the character set forth, the combination of wick raising means, a member adapted to be engaged and moved by the wick, and connections established by 85 the initial movement of said member whereby the member is moved by the wick raising means out of contact with the wick, a dwell in the movement of the wick is effected, and the movement of the wick subsequent to the dwell is limited. 90

4. In a burner of the character set forth, the combination of wick raising means capable of being thrown into and out of operative connection with the wick, a member 95 adapted to be engaged and moved by the wick when the latter is elevated, connections established between said member and the wick raising means when said member has been initially lifted whereby the wick raising means is instrumental in further lifting said member free from the wick, said connections serving, during the entire movement of the member, to temporarily disconnect the wick raising means from the wick 100 so that a dwell in the movement of the wick is effected, and stop mechanism operatively connected to the wick raising means by the movement of the aforesaid member. 105

5. In a burner of the character set forth, the combination of a wick, a prime mover, separable connections between the prime mover and wick, a member adapted to be engaged and initially moved by the wick, 110 connections established between the prime mover and said member through the initial movement of the member whereby the member is moved away from the wick by the prime mover, and mechanism actuated by the movement of said member for temporarily rendering inoperative the connections between the prime mover and wick. 115

6. In a burner of the character set forth, the combination with a prime mover, wick raising means, separable connections between the prime mover and said means, a member adapted to be engaged and moved by the wick when the wick is elevated, operative connections adapted to be established between said member and the prime 120 125 130

1
mover when the member is initially moved by the wick whereby said member may be elevated out of contact with the wick by the prime mover, mechanism actuated when 5 the aforesaid connections are made and during the elevation of said member for temporarily disconnecting the wick raising means from the prime mover, and stop means operatively connected to the prime 10 mover through the effecting of the aforesaid connections between the member and the prime mover.

7. In a burner of the character set forth, the combination of a wick carrier, a rack 15 operatively connected thereto, a pinion meshing with the rack, a spindle whereon the pinion is loosely mounted, a clutch for establishing driving connection between the spindle and pinion, a member disposed in 20 the path of the wick and adapted to be engaged and moved thereby when the wick is elevated, a gear secured to the spindle, an element movable with the aforesaid member and having a tooth adapted to be brought 25 into mesh with the gear when the element is moved by the aforesaid member, stop mechanism carried by said element and incorporating a toothed member having a limited movement and adapted to be brought 30 into cooperation with the gear when the element is moved by the gear, and operative connection between the element and the aforesaid clutch whereby the clutch is disengaged during a part of the movement of 35 the element.

8. In a burner of the character set forth, the combination with a wick carrier, a rack operatively connected thereto, a pinion meshing with the rack, a spindle whereon 40 the pinion is loosely mounted, a clutch through which driving connection is established between the pinion and the spindle, a gear on the spindle of a radius greater than that of the pinion, a member in the 45 path of the wick adapted to be engaged and moved thereby when the wick is elevated, an element connected to and movable with said member and having a tooth adapted to be brought into mesh with the 50 gear when the member is initially elevated by the wick, mechanism actuated by the element during a part of the latter's movement for temporarily disengaging the aforesaid clutch and thus suspending driving 55 connections between the spindle and the pinion, and stop mechanism acting upon

the aforesaid gear for limiting the rotation of the spindle and moved into mesh with said gear when the aforesaid element is elevated.

9. In a burner of the character set forth, the combination of a wick carrier, a rack operatively connected thereto, a spindle, a pinion secured to the spindle and into and out of engagement with which the aforesaid rack is adapted to be moved, means tending to move the rack into engagement with the spindle, a member arranged in the path of the wick and adapted to be engaged and moved thereby when the wick is elevated, an element movable with said member and having a tooth adapted to be brought into mesh with the teeth of the pinion when the element is initially moved, the pinion thereafter serving to elevate the element and aforesaid member independently of the wick, means serving to shift the element laterally during its elevation, the element cooperating with the rack in such manner as to temporarily disengage the rack from the pinion while the element is shifted laterally, and stop mechanism thrown into mesh with the pinion by the elevation of the said element and which serves to limit rotation of the pinion in a direction to elevate the wick.

10. In a burner of the character set forth, the combination of wick raising means, a flame spreader adapted to be engaged and moved by the wick, operative connections, established by the initial movement of the flame spreader, between it and the wick raising means whereby the spreader is lifted by said means out of contact with the wick and a dwell in the movement of the wick is effected, and stop mechanism incorporated in said connections that is coupled to the wick raising means through the action of the connections.

11. In a burner of the character set forth, the combination of wick raising means, a flame spreader arranged to be engaged and moved by the wick, and operative connections, established by the initial movement of the flame spreader, between it and the wick raising means for effecting a dwell in the movement of the wick, a withdrawal of the flame spreader from the wick, and a stopping of the wick raising means.

In testimony whereof, I hereunto affix my signature.

LEE S. CHADWICK.
